UNITED STATES PATENT OFFICE.

FOREST A. RAY, OF BOSTON, MASSACHUSETTS.

GAS-LAMP.

No. 818,790.

Specification of Letters Patent.

Patented April 24, 1906.

Application filed December 31, 1904. Serial No. 239,091.

To all whom it may concern:

Be it known that I, FOREST A. RAY, a resident of Boston, in the county of Suffolk and State of Massachusetts, have invented certain new and useful Improvements in Gas-Lamps, of which the following is a specification.

This invention relates to gas-lamps of the incandescent-mantle type having a cluster of lights and means for supplying a mixture of gas and air to burners for the purpose of producing light by raising the mantles to a temperature of incandescence by the heat of the flame at the burners.

15 The present invention comprises an improved structure in which the gas before it is mixed with the air and before being carried to the burners is heated to a high temperature, and thereby expanded in volume, thus 20 increasing its ability to entrain air and causing an increase in the temperature of the flame, resulting in a greater intensity of incandescence in the mantles and a more brilliant light.

25 The details of the invention are hereinafter described, and illustrated in the accompanying drawings, in which—

Figure 1 represents a longitudinal section of a lamp embodying the principles of the invention. Figs. 2 and 3 represent cross-sections on lines 2 2 and 3 3, respectively, of Fig. 1. Fig. 4 represents a longitudinal section, on an enlarged scale, of the Bunsen tube for supplying the gas and air to the burners and 35 gas outlet and regulator for furnishing the gas, the section being taken on a plane at right angles to that of Fig. 1.

The same reference characters indicate the same parts in all the figures.

40 1 is a pipe which constitutes the main conduit for the gas-supply and is also the support for the other parts of the lamp. The upper portion of the pipe may be provided with a fitting for attaching it to a gas-main or 45 with any other suitable holder for supporting it and preferably extends downwardly therefrom, terminating at 2, at which point there is attached an outlet and a check or regulating valve therefor, through which a stream 50 of gas may be projected. The outlet consists of a tubular member 3, having a socket 4 screwed upon the end 2 of the main conduit and having outlet-passages 5 at its lower end. In line with the axis of the tubular member 3 55 is a projection 6, of which the base or that

portion which is attached to the member or nozzle 3 is cylindrical, while its outer portion 7 is conically tapered to a point. A regulator or check consisting of a sleeve 8 is mounted so as to be longitudinally movable upon the 60 tubular part 3 and has a projecting end over which extends a diaphragm 9, having a central orifice 10 in line with the projection 6. The diameter of the hole is approximately the same as that of the cylindrical part of the 65 projection 6, and the range of adjustment of the sleeve 8 on the tubular portion 3 is such that it can be moved upwardly until the cylindrical part of the projection extends through the hole or it can be moved downwardly until the diaphragm is entirely below the point of the projection, thus varying the size of the outlet from the full diameter of the orifice 10 to the difference between the diameters of the orifice and the projection, which 70 is very slight, thereby affording a perfect regulation of the flow of gas from the outlet. Having the orifice 10 of substantially the same diameter as the cylindrical part of projection 6 affords a means by which the orifice 80 can be kept free of dirt, &c., as by adjusting the sleeve upward until the diaphragm extends over the said cylindrical portion the latter will force out any accumulations which might have gathered upon the sides of the 85 orifice.

Upon the outside of the socket 4 is secured a depending tube 11, to the lower end of which is detachably fastened in any suitable manner, as by a screw-thread, as shown in 90 the drawings, a burner-support 12, which has passages extending upwardly to outlets 13, in which are mounted the burners 14. Between its point of attachment to the burner-support and the gas-outlet 3 the tube 11 is 95 provided with openings 15, extending through its sides, permitting the flow of the outer air to its interior when a jet of gas is projected from the outlet 3 into the tube, whereby entrainment of air by the jet of gas is caused. 100 The tube 11 thus constitutes a Bunsen tube which supplies the mixture of gas and air to the burners. In order to provide sufficient length to the tube to secure proper entrainment of the air, an extension to the tube is 105 provided in the form of a sleeve 16, which is revolvably mounted in the tube for a purpose to be described and extends downwardly therefrom and through the lower portion of the burner-support 12, its outwardly-extend- 110

12
ing portion being provided with a handle or hand-engaging member 17, by which it may be rotated.

Tube 16 is extended with an unbroken surface 5 face a distance sufficient for the jet of gas in diverging as it emerges from the orifice 10 to impinge against the sides of the tube, and below the point of impingement the tube has openings 18, permitting the mixture of air and gas to flow out into the annular space 19 between the tube and the lower portion of the burner-support 12, the said space communicating with the passages leading to the outlets 13. The joint between the lower part of the burner-support and the outwardly-projecting portion of the tube 16 is packed, so as to prevent leakage of gas through the joint and at the same time permit rotation of the tube, such packing means consisting of an annular sleeve or gland 20, threaded upon a tubular flange 21, surrounding the tube 16, packing 22, interposed between the end of said flange, and a shoulder 23 on the sleeve 20. The point of connection of the Bunsen tube to the burner-support constitutes a gas and air inlet to the latter and is located at the center thereof, while the outlets are arranged symmetrically about the inlet. There are at least two outlets and may be as many more as desired, and in each of these is mounted a burner which extends upwardly closely adjacent to the conduit 1 and surrounding the same. Mantles 24 are supported above the burners by a support consisting of a collar 25, 30 adjustably mounted upon the conduit and having radial arms 26 extending outwardly over the burners and supporting mantle-holders 27, which have outer hooked portions 28 and inner portions 29 extended through holes in the arms 26, the part between the portions 28 and 29 extending horizontally outward, being supported on the upper surfaces and retained between projections 30, mounted upon the arms. Interposed in the conduit 1 above the mantle-support 25 is a valve 31, by which the flow of gas to the burners may be interrupted, and connected to the conduit above the valve is a pilot-burner tube 32, which extends downward and terminates in a burner 33 adjacent the main burners 14. This burner always receives gas from the conduits whether or not the supply to the main burner is cut off and constantly maintains a pilot-light in position to ignite the flame at the main burners as soon as the supply is turned on.

The valve 31 is controlled by a bar 34 and operating members 35 and 36, connected to the ends of the controller-bar and depending therefrom, their lower ends having hand-engaging portions 37 and 38 hanging below the burner-support.

A translucent globe or chimney 39, extending from above the mantles to below the burners and surrounding the same, is sup-

ported upon a globe-support 40, which comprises a collar 41, surrounding the lower portion of the burner-support and clamped thereto by a set-screw 42, the collar having radial arms 43, which engage with lugs or straps 44, mounted upon a collar 45, which surrounds and may be connected to the lower part of the globe 39, or it may loosely surround the lower end of the globe. The upper end of the globe or chimney is attached by set-screws 46 to a tube 47, rigidly connected to the arms 48 of a yoke slidingly mounted upon the conduit 1, the arms 48 extending radially outward from a sleeve or collar 49, surrounding the conduit 1 and being bent downwardly and extending to the tube 47.

The lugs 44 are retained in connection with the arms 43 by gravity only, and the collar 49 is free to slide upon the conduit 1. Therefore when the globe is raised a slight amount and turned, so as to move the lugs 44 clear of the ends of the arms 43, the globe and yoke may be slid downwardly until collar 49 bears against the coupling 50, in which is mounted the valve 31. Preferably the arms 48 and tube 47 are long enough so that when collar 49 is in contact with the coupling 50 the globe 39 is below the burner-support in position where its interior is readily accessible, so that it can be cleaned. The globe may also be raised above the mantle-support and the collar 49 secured in any suitable manner to hold it in such position in order to provide access to the mantles and burners for renewing broken mantles. On the ends of arms 43 are upstanding portions 51, which prevent rotation of the globe to separate the lugs or straps from the arms until the latter have been raised above the said projections. Two of the arms forming part of the globe-support 40 have also guideways 52, through which extend the lower portions of the controller-operating members 35 and 36, whereby the globe-support constitutes a guide for the valve-operating members.

The tube 16 in addition to being an extension of the Bunsen tube constitutes also a regulating means for the gas-check sleeve 8, and it is for this purpose that it is mounted revolubly in the tube 11 and extends below the lower part of the burner-support. A connection between the sleeve 8 and tube 16 is afforded by means of bars 53, which are connected to the sleeve 8 and tube 16, so that rotation of the tube turns the sleeve on the tubular member 3, causing it by means of its threaded engagement therewith to ride up and down upon the tubular member 3.

The apparatus works upon the same principle as that involved in the lamp illustrated and described in an application, Serial No. 239,090, filed by me concurrently with the present one—that is, the principle of heating and thereby expanding the gas before it is

delivered from the conduit into the Bunsen tube—but this device differs from the one of the application referred to and is an improvement over the same in that the outlet for the 5 gas from the conduit is arranged in close proximity to the burners, so that there is very little opportunity for the gas to be cooled after it leaves the conduit. As heating the 10 gas increases its volume and diminishes its density, a larger size of aperture in the gas-regulator is necessary to permit the same actual quantity of gas flowing through the outlet when hot than when at a normal temperature. Consequently when the same quantity 15 of heated gas is being discharged the jet is larger than when the gas is cold or at the normal temperature, and therefore a greater volume of air in proportion to the actual quantity of gas is entrained and forced into 20 the burner-support with the gas. I have found that the amount of air entrained varies approximately in proportion to the increase in volume of the gas due to heating, and consequently if the gas is sufficiently heated to 25 double the volume almost double the quantity of air will be drawn in by the gas in its heated condition than is done by the same quantity of gas when cold. As the flame at the burners becomes hotter in proportion to 30 the increase in the proportion of air entrained and also is made hotter as the jet before being delivered to the burners is raised in temperature and pressure, it is evident that the preliminary heating of the gas-jet is 35 a very important feature, and it is also important that as little opportunity as possible should be given for the gas to become cooled again before it reaches the air-entraining point and for the mixture of air and gas to 40 cool before reaching the burners. For this reason I have located the outlet from the gas-supplying conduit as near to the burners as is practicable and safe, it being so near that the heat supplied to it from the burners is of as 45 great an intensity as can possibly be given without danger of igniting the jet before it is delivered into the Bunsen tube and the inlet for the entrained air closely adjacent. As is evident from the drawings, the gas-outlet 5 and air-inlet 15 are at the same level as the burner members 14, while the gas-outlet is approximately on the level of the outlets from the burners, where they are ignited, being located only a sufficient distance below 55 them to insure against ignition of the jet. So far as I am aware I am the first who has utilized this principle of increasing the volume of air entrained by raising the temperature and volume of the gas-jet. The hand- 60 engaging member 17 inserted in and closing the bore of tube 16 acts as a baffle which arrests the jet of gas and air and causes the same to become thoroughly mixed before passing out through the openings 18 to the 65 passage or space 19.

I claim—

1. A gas-lamp having a burner, a mixing-tube having an air-inlet and connected to permit the flow of a mixture of gas and air therefrom to the burner located beside the 70 burner, and a gas-conduit arranged to discharge into the tube at approximately the level of and located in close proximity to the flame of the burner.

2. A gas-lamp having a burner, a gas-conduit located beside the burner closely adjacent the same, a mixing-tube in line with and forming a continuation of the conduit having a connection at one end with the burner and at its other end provisions for admitting air, 80 and a contracted outlet to said conduit in line with said tube adjacent the air-admitting portion thereof.

3. A gas-lamp comprising a burner, a mixing-tube connected thereto, and means for 85 forcing a jet of gas into said tube in the direction of its length and admitting air into the tube, at a point substantially on the level of the burner and close beside the same.

4. A gas-lamp comprising a burner-sup- 90 port, a plurality of burners mounted thereon, a mixing-tube connected at its lower end to the burner-support and located centrally among the burners in close proximity to each, having an air-inlet adjacent its other end, 95 and a gas-conduit having an outlet adjacent the air-inlet of said tube and arranged to direct a jet of gas into the tube.

5. A gas-lamp comprising a burner-sup- 100 port having a single central inlet thereto and a plurality of outlets therefrom symmetrically arranged about the inlet, a tube, having provisions for the admission of air, connected to the inlet, a gas-supplying conduit arranged in line with said tube adapted to project a jet 105 of gas into the same, the outlet for the jet from said conduit being substantially at the level of the burners, and burners connected to the outlets from said burner-support adjacent said conduit. 110

6. A gas-lamp comprising a burner-sup- 115 port having a single central inlet thereto and a plurality of outlets therefrom symmetrically arranged about the inlet, a tube, having provisions for the admission of air, connected to the inlet, a gas-supplying conduit arranged in line with said tube adapted to project a jet of gas into the same, the outlet for the jet from said conduit being substantially at the level of the burners, burners connected to the outlets 120 from said burner-support adjacent said conduit, and mantles supported by said conduit above said burners.

7. A gas-lamp comprising a burner-sup- 125 port having a single central inlet thereto and a plurality of outlets therefrom symmetrically arranged about the inlet, a tube, having provisions for the admission of air, connected to the inlet, a gas-supplying conduit arranged to project a jet of gas into said tube at a point 130

approximately at the level of the burners, and an adjustable valve or regulator for regulating the amount of gas delivered from the conduit.

5. A gas-lamp comprising a burner-support having a single central inlet thereto and a plurality of outlets therefrom symmetrically arranged about the inlet, a tube, having provisions for the admission of air, connected to the inlet, a gas-supplying conduit arranged to project a jet of gas into said tube, an adjustable valve or regulator for regulating the amount of gas delivered from the conduit, the air-admission, gas-jet and valve being approximately at the level of the burners, and external means connected to said valve for adjusting the same.

9. A gas-lamp comprising a burner-support, burners mounted thereon, said support having an inlet centrally arranged with respect to said burners and passages leading therefrom to the burners, a tube connected to said inlet and extended therefrom having provisions for admission of air thereto, a gas-conduit connected to said tube, an outlet-valve therefor located in the tube, and means external to the tube and burner-support for adjusting said valve to regulate the flow of gas.

30. 10. A gas-lamp comprising a burner-support, burners mounted thereon, said support having an inlet centrally arranged with respect to said burners and passages leading therefrom to the burners, a tube connected to said inlet and extended therefrom having provisions for admission of air thereto, a gas-conduit connected to said tube and having an outlet arranged to project a jet of gas into the tube, and a tube forming an extension of said before-mentioned tube extending into the interior of the burner-support.

11. A gas-lamp comprising a burner-support, burners mounted thereon, said support having an inlet centrally arranged with respect to said burners and passages leading therefrom to the burners, a tube connected to said inlet and extended therefrom having provisions for admission of air thereto, a gas-conduit connected to said tube and having an outlet arranged to project a jet of gas into the tube, an additional tube revolvably mounted in the above-named tube extending through the burner-support, a regulating-valve arranged in the outlet from said gas-conduit, and connections between said valve and the revolvable tube.

12. A gas-lamp comprising a burner-support, burners mounted thereon, said support having an inlet centrally arranged with respect to said burners and passages leading therefrom to the burners, a tube connected to said inlet and extended therefrom having provisions for admission of air thereto, a gas-conduit connected to said tube and having an outlet arranged to project a jet of gas into

the tube, an additional tube revolvably mounted in the above-named tube extending through the burner-support, packing means surrounding the portion of the revolvable tube projecting from the burner-support and connected to said support for preventing leakage between the tube and support, a handle connected to said projecting portion of the revolvable tube, a regulating-valve arranged in the outlet from said gas-conduit, and connections between said valve and the revolvable tube.

13. In a gas-lamp, a burner-support carrying upwardly-extending burners, and having an inlet, an upwardly-extending tube, having provisions for admitting air to its interior, mounted in the inlet, and a gas-conduit connected to said tube closely adjacent the burners among the same and arranged to project a jet of gas downwardly into said tube.

14. A gas-lamp comprising a gas-supplying conduit constituting a support, an outlet at the end thereof, a gas check or regulator for said outlet, a tube connected to said conduit and surrounding the outlet and gas-check, a burner-support connected to said tube below the gas-outlet, burners mounted on said burner-support beside the conduit, said tube having provisions for the admission of the atmosphere to its interior, and the support having passages leading from the tube to the burners, and mantles supported by the conduit over the burners.

15. A gas-lamp comprising a gas-supplying conduit constituting a support, an outlet at the end thereof, a gas check or regulator for said outlet, a tube connected to said conduit and surrounding the outlet and gas-check, a burner-support connected to said tube below the gas-outlet, burners mounted on said burner-support beside the conduit, said tube having provisions for the admission of the atmosphere to its interior and the support having passages leading from the tube to the burners, mantles supported by the conduit over the burners, a lower globe-support rigidly mounted on the burner-support beneath the burners, an upper globe-support slidingly mounted on the conduit above the mantles, and a transparent globe connected to said upper support and resting upon said lower support inclosing the burners and mantles.

16. A gas-lamp comprising a gas-supplying conduit constituting a support, an outlet at the end thereof, a gas check or regulator for said outlet, a tube connected to said conduit and surrounding the outlet and gas-check, a burner-support connected to said tube below the gas-outlet, burners mounted on said burner-support beside the conduit, said tube having provisions for the admission of the atmosphere to its interior and the support having passages leading from the tube to the burners, mantles supported by the conduit over the burners, a lower globe-support having radial arms rigidly mounted on the

burner-support beneath the burners, an upper globe-support slidingly mounted on the conduit above the mantles, a globe inclosing the burners and mantles connected to said upper support, and a collar connected to the bottom of the globe provided with lugs adapted to engage and rest upon the arms of the lower support.

17. A gas-lamp comprising a gas-supplying conduit, a valve therein, a controller-bar connected to said valve, operating members for said bar connected thereto and depending therefrom, guides for the lower portions of said operating members, a Bunsen tube connected to the lower end of the conduit, a burner-support connected to said Bunsen tube, and burners mounted on said burner-support.

18. A gas-lamp comprising a gas-supplying conduit, a Bunsen tube connected to the lower end of said conduit and a gas-outlet from the conduit into the Bunsen tube, a burner-support connected to said Bunsen tube, burners mounted thereon located beside the conduit, mantles supported by the conduit above said burners, a valve in said conduit above the gas-outlet for interrupting the flow of gas to the burners, a pilot-burner connected to the conduit above the valve, and a controller for operating said valve.

19. A gas-lamp comprising a gas-supplying conduit, a Bunsen tube connected to the lower end of said conduit and a gas-outlet from the conduit into the Bunsen tube, a burner-support connected to said Bunsen tube, burners mounted thereon located beside the conduit, mantles supported by the conduit above said burners, a valve in said conduit above the gas-outlet for interrupting the flow of gas to the burners, a pilot-burner connected to the conduit above the valve, a controller-bar connected to said valve, depending operating members connected to the ends of said bar, a globe or chimney surrounding the burners and mantles, and a support for the lower portion of said globe, said support having provisions for guiding the lower portions of the depending controller-operating members.

20. A gas-lamp comprising a gas-supplying conduit, a burner located in close proximity to the conduit whereby the latter is heated

and the gas therein expanded, a Bunsen tube connected to deliver a mixture of gas and air to the burner, and an outlet connected to 55 said conduit closely adjacent and approximately at the level of the burner and arranged to project a jet of gas into said tube.

21. In a lamp having a burner-support, burners and a globe inclosing said burners, a 60 support for the globe comprising a member mounted on the burner-support having laterally-extending arms provided with upward projections, and a member of greater lateral extent than the arms of said first-named 65 member adapted to be engaged with the lower edge of said globe and provided with inwardly-extending lugs arranged to be engaged with the ends of said arms, and to be disengaged therefrom by being raised and 70 rotated a slight amount.

22. In a lamp having a burner-support, burners and a globe inclosing said burners, a support for the globe comprising a member mounted on the burner-support having laterally-extending arms provided with upward projections, and a ring greater in diameter than the lateral extent of said first-named member adapted to be engaged with the lower edge of said globe and provided 75 with inwardly-extending lugs arranged to be engaged with the projections on the ends of said arms and to be disengaged therefrom by being raised and rotated a slight amount.

23. In a lamp having a central main support, a burner-support connected beneath the main support, and burners mounted on said burner-support, a member slidingly engaged with the main support above the burners and adapted to serve as a holder and guide for the 85 upper portion of a globe, a globe inclosing the burners detachably connected to the said member, and a support for the globe comprising a clamp connected to the burner-support below the burners, arms extending therefrom and a ring engaged with the lower portion of said globe having inwardly-extending 90 portions detachably engaged with said arms. 95

In testimony whereof I have affixed my signature in presence of two witnesses.

FOREST A. RAY.
